ACTUATING MEANS FOR AN OPERATING MECHANISM FOR PIVOTED CLOSURES OF A JALOUSIE WINDOW

Robert S. Cline, Bradenton, Fla., assignor to V. E. Anderson Manufacturing Company, Inc., Bradenton, Fla., a corporation of Kentucky

Filed June 23, 1958, Ser. No. 743,915

21 Claims. (Cl. 20—62)

This invention relates generally to actuating means for an operating mechanism for pivoted closures, such as the pivoted panes of a jalousie window, and constitutes a continuation in part of my application filed June 3, 1957, and bearing Serial No. 663,169, now Patent 2,930,251 dated March 29, 1960.

One of the essential objects of the invention is to provide actuating means of the type mentioned that may be employed either in an original installation of the jalousie window, or as a replacement for a different form or type of actuating means previously installed.

Another object is to provide actuating means including an actuating bar and an adaptor structure pivotally connected thereto and including adjustable means capable of being attached to a connecting bar of the jalousie operating mechanism at the former point of attachment of the previously installed actuating means, whereby the new actuating means or replacement may be readily installed with the previously installed jalousie operating mechanism without alterations thereto.

Another object is to provide an adaptor structure wherein the adjustable means includes a nut and a cylindrical axial extension thereof that are slideable lengthwise of the body of the adaptor and have registering openings therein adapted to register with the former point of attachment for the previously installed actuating means, or with the proper predetermined point of attachment for the actuating means of an original installation.

Another object is to provide an adaptor structure wherein a part of the body of the adaptor is shaped to guide the nut during sliding movement thereof, and is operable to prevent the nut from turning during such sliding movement.

Another object is to provide an adaptor wherein the cylindrical axial extension of the nut is within and movable lengthwise of an elongated longitudinally extending slot in the body of the adaptor, and wherein the registering openings aforesaid in the nut and extension are adapted to receive a fastening element by which the adaptor may be attached to the connecting bar of the jalousie operating mechanism at the former point of attachment for the previously installed actuating means, or with the proper predetermined point of attachment for the actuating means of an original installation.

Another object is to provide an adaptor wherein the body is provided at one end of the elongated slot with a circular opening to permit original insertion or entry of the cylindrical extension into said slot via said circular opening, and wherein a portion of the body at an edge of the circular opening is distorted after the cylindrical extension has entered the elongated slot via the circular opening, to provide a projection operable to prevent the cylindrical extension from subsequently registering with and being accidentally withdrawn from said circular opening.

Another object is to provide an adaptor wherein the body is provided at the edges of said elongated slot beyond said circular opening with a continuous guide flange

2

that engages an annular groove in said extension during sliding movement of the nut, and retains the nut and cylindrical extension against displacement.

Another object is to provide an adaptor wherein the body thereof is provided with means engageable with the connecting bar of the jalousie operating mechanism to guide the adaptor lengthwise of said connecting bar to establish proper registration of the nut and cylindrical extension aforesaid with the former point of attachment for the previously installed actuating means, or with the proper predetermined point of attachment for the actuating means of an original installation.

Another object is to provide an actuating means, including an adaptor structure, that is simple in construction, economical to manufacture, easy to install, and efficient in operation.

Other objects, advantages and novel details of construction of this invention will be made more apparent as this description proceeds, especially when considered in connection with the accompanying drawings wherein:

Figs. 1 and 2 are vertical sections through a jalousie window and showing the end members for the panes thereof in opened and in closed positions respectively.

Fig. 3 is a fragmentary front elevation of the jalousie window illustrated in Figs. 1 and 2.

Fig. 4 is an enlarged fragmentary sectional view through the operator in an axial plane thereof.

Fig. 5 is a cross section on line 5—5 of Fig. 4. Fig. 6 is a fragmentary elevation of a lever handle, and illustrating the rock arm in full and dotted lines respectively, to show the different positions in which the lever handle and rock arm may be assembled when the operator is changed from one side to the other of the jalousie frame.

Fig. 7 is a fragmentary elevation of the operator, showing the bearing member for the lever handle attached to a side rail of the jalousie frame and concealing the slot or cutaway portion therein, and showing parts broken away and in section.

Fig. 8 is a vertical sectional view through a side rail of the jalousie frame not used for the operator mounting, and showing a blank for concealing the slot or cutaway portion in said side rail.

Fig. 9 is a fragmentary sectional elevation of a side rail, taken from the inner side thereof and showing the actuating bar for the jalousie operating mechanism in locked position.

Fig. 10 is a detached enlarged front elevation of the adaptor structure and including the adjustable connecting means between the operator and the jalousie operating mechanism, and showing the cylindrical extension of the nut in registration with the circular opening.

Fig. 11 is a cross sectional view taken substantially on the line 11—11 of Fig. 1.

Fig. 12 is a view similar to Fig. 10, but showing the cylindrical extension of the nut held by the projection out of registration with the circular opening.

Fig. 13 is a perspective view of the adaptor structure and actuating bar, with a portion of the latter broken away.

Fig. 14 is a view similar to Fig. 12, but showing a slightly modified construction.

Fig. 15 is a cross sectional view through the adaptor structure illustrated in Fig. 14 and through a connecting bar fastened thereto.

Jalousie windows are controlled by various types of operators, and certain of said operators are movable in vertical slots in the jalousie frame. In my invention, the mechanism is actuated by a rotatively movable lever handle located in a convenient position on the jalousie frame. If such construction is used as a replacement for another type of operator, and one in which the jal-

ousie frame is slotted, it is desirable to conceal this slot. Therefore, I have devised a construction in which the operator unit is mounted on a side rail of the jalousie frame to engage and conceal a slot or cutaway portion therein and to form a rigid attachment to the side rail.

Generally described, the operator includes a cast aluminum alloy lever handle 10 pivotally mounted on a bearing member 11 having a portion 12 fitting within a slot or cutaway portion 13 in a side rail 14 of the jalousie frame. The side rail 14 is formed of an extruded aluminum channel bar which receives and conceals portions of the operating mechanism, and the lever handle 10 is mounted at the front of said side rail on an angle flange 15 thereof adjacent to a transversely extending web portion 17. To impart the requisite strength to the handle 10, it has cast within a hub portion 18 thereof a polygonal pin 19, preferably hexagonal, formed of harder metal and coaxial with the hub 18. Such pin 19 has a polygonal portion 20 extending outward beyond the hub 18. The pin 19 has a reduced portion 21 within the hub 18, and a part 22 of said hub encircles the reduced portion 21 and forms an anchor for holding the pin 19 from axial displacement. Beyond the polygonal portion 20 is an end portion 23 that is further reduced in diameter and is threaded.

Non-rotatably sleeved upon the polygonal portion 20 of the pin 19 is a bushing 24 which interiorly conforms to and fits about the polygonal exterior of the portion 20 of the pin, but is externally cylindrical to rotate within a bore 25 in a hub 26 of the bearing member 11.

A rock arm 30 is rigidly secured to an outer projecting end portion 31 of the bushing 24, so that when the latter is engaged with the polygonal portion 20 of the pin, a torque transmitting connection is formed between the handle 10 and the rock arm 30.

The bearing member 11 is of a length somewhat greater than that of the slot 13 in the rail 14 and has at opposite ends thereof portions 32 which overlap the side rail and are attached thereto by screws 33. However, the portion 12 within the slot 13 in the side rail will receive the maximum operating stresses and not the screws 33.

To mount the handle 10 on the bearing member 11, the projecting polygonal portion 20 of the pin is first inserted from the outside of the side rail 14 into the bore 25. The bushing 24 is then sleeved upon the polygonal portion 20 of said pin from the inside of the side rail and is held against displacement by a nut 34 engaging the threaded end portion 23.

The rock arm 30 is connected by a substantially aligned flat actuating bar 40 to the jalousie operating mechanism.

The separate panes 41 of the jalousie are mounted in metallic end members 42 which are pivotally attached at 43 to the side rail 14. Actuating arms 44 extend on the opposite side of the pivots 43 and are connected to the back of a channel-shaped common connecting bar 45. Thus a movement of said connecting bar 45 longitudinally will simultaneously turn each of the members 42 on their pivots from the closed position where the pins 41 overlap each other as shown in Fig. 2, to the open position shown in Fig. 1 or vice versa as desired.

Without further description of the jalousie, its connection to the operator is through the actuating bar 40 that is pivotally connected at its lower end by a headed pivot pin 46 to the rock arm 30, and is pivotally connected at its upper end by a headed pivot pin 47 to an adaptor structure 48 mounted on the connecting bar 45. A suitable socket 47' is provided in a longitudinal side edge of the body 54 of the adaptor structure 48 to receive the shank of the headed pivot pin 47. Thus the rocking movement of the handle 10 will be transmitted through the rock arm 30, actuating bar 40, and adaptor structure 48 to the connecting bar 45 to operate the end members 42 and panes 41 of the jalousie window.

As my improved actuating means for an operating mechanism is sometimes used as a replacement for that of a previously installed jalousie, it is desirable to provide adjustment for the connections. Thus as shown in Fig. 5 11, the connecting bar 45 may have a bore 49 therethrough for engaging a pivot of the old operator, and this bore may be utilized for the attachment of the adaptor structure 48. However, its position may not be right to fit the new installation. Therefore, I have provided 10 a headed pin 50 having a cylindrical portion 51 for engaging said bore 49 wherever located, and having a threaded shank 52 for passing through a longitudinally extending elongated slot 53 in the body 54 of the adaptor structure 48. In this connection, the former point of attachment for the previously installed actuating means, or the point of attachment for the actuating means of an original installation may be at the same or different locations in or on the connecting bar 45, as desired. As shown, only one point of attachment is illustrated, 15 because both points above mentioned are at the same location.

A polygonal nut 56 having a threaded opening 56' therethrough is on one side of the body 54 beside a longitudinally extending flange 57 which holds said nut from 20 turning while guiding the movement of the nut lengthwise of the flange 57, and thereby guiding the pin 50 lengthwise of the elongated slot 53. The nut 56 is provided at one side thereof with a cylindrical axial extension 58 which is initially inserted through a circular opening 59 at the upper end of the slot 53, and then 25 engages the elongated slot 53. This extension 58 has an annular groove 60 therein which receives a continuous guide flange 61 that extends along the edges of said slot at opposite sides and at the bottom thereof below 30 said circular opening 59. Thus the nut 56 may be assembled with the body 54 by first inserting the cylindrical extension 58 in the circular opening 59 and then moving the extension 58 longitudinally of the slot 53, so that the groove 60 will receive the guide flange 61. To 35 prevent accidental disengagement of the nut 56 after engagement of the annular groove 60 with the flange 61, the upper edge of the opening 58 is pinched or otherwise deformed to provide a projection 62 that serves 40 as an abutment for the cylindrical extension 58 and effectively prevents subsequent registration or alignment 45 of said cylindrical extension 58 with the circular opening 59. However, the cylindrical extension 58 of the nut is then free to slide lengthwise of the slot 53 between the projection 62 and the lower end of said slot. Thus 50 the projection 62 prevents the return of the cylindrical extension 58 to its position of entry in the circular opening 59.

Laterally projecting lugs 70 and 71 respectively at the upper and lower ends of one side of the body 54 of the adaptor structure 48 slidably engage the channel of the connecting bar 45 to guide the body 54 of the adaptor structure 55 longitudinally of said bar. A longitudinally extending flange 75 of the body 54 of the adaptor structure is spaced from and cooperates with the lugs 70 and 71 to guide the body 54 of the adaptor structure 48 lengthwise of the channel-shaped connecting bar 45. Such flange 75 slidably engages one longitudinal side edge 60 of said connecting bar 45.

The assembled parts just described, together with the 65 other portions of the operator may be shipped as a unit to wherever it is to be installed and without danger of loss of any parts through accidental disengagement.

To attach the operator to the jalousie, the pin 50 is 70 unscrewed and detached from the nut 56 so that said pin may be inserted into the bore 49 of the connecting bar 45. The threaded shank 52 is then re-engaged with the nut 56 after the latter has been slid lengthwise of the slot 53 to the proper location in registration 75 with the bore 49, and upon tightening the pin 50, the

adaptor structure 48 will be connected to the connecting bar 45.

When the end members 42 and panes 41 of the jalousie are closed, it is desirable to lock them in such closed position. This may be accomplished as illustrated in Fig. 9 in which the rock arm 30 is turned by the lever handle 10 into a position where the upper end of the rock arm abuts and is stopped by the web portion 17 of the side rail 14. In this position, the pivotal connection 46 has passed beyond its dead center, and the end members 42 of the jalousie window are in closed position. Actually, the arrangement of the bushing 24 and the pivotal connections 46 and 47 is such that the upper end portion of the rock arm 30 will be held in contact with the web portion 17 after the pivotal connection 46 is beyond its dead center, and accordingly the actuating bar 40 and jalousie operating mechanism will be locked in closed position.

A change of the operator from one side to the other of the jalousie frame, such for example from the right side to the left side of the jalousie frame, would cause the lever handle 10 to be in the wrong angular relation or position to the rock arm 30, bearing member 11 and side rail 14. To avoid such result, the lever handle 10 and the rock arm 30 are relatively positioned with an included angle therebetween which is one-half the angular magnitude between adjacent sides of the polygonal portion 20 of the pin. Also, the lever handle 10 and rock arm 30 are positioned relative to the polygonal portion 20 of the pin so that the lever handle 10 may be changed from a given angle on one side of the rock arm 30 to an equal angle on the opposite side thereof, by first disassembling or withdrawing the polygonal portion 20 of the pin from the bushing 24 fixed to the rock arm 30, then turning or shifting the lever handle 10 from one side to the opposite side of the rock arm 30, so that the polygonal portion 20 will be turned or shifted from one side to the next, and then assembling or inserting the turned or shifted polygonal portion 20 in the bushing 24 to retain the lever handle 10 in its new angular position relative to the rock arm 30. The different positions in which the lever handle 10 and rock arm 30 may be assembled are illustrated in full and in dotted lines respectively in Fig. 6. Thus, the locations of the lever handle 10 in open and in closed positions of the end members 42 and panes 41 of the jalousie may be made the same relative to opposite sides of the jalousie frame when mounted on the right and left sides respectively thereof.

The operator may be easily applied for operation of any jalousie construction. If it is used to replace operators which necessitate the slotting or cutting away of the side rails 14 of the jalousie frame, the bearing member 11 will cover such slot or cutaway portion. If the rails on both sides of the jalousie frame have been or are slotted, the bearing member 11 may be used to cover the slot in the side rail 14 where the operator is mounted, and a solid blank 80 similar in shape to the bearing member 11 may be used, as illustrated in Fig. 8, for closing the slot or cut-out in the other side rail on which the operator is not mounted.

In Figs. 14 and 15 respectively, I have shown a slightly modified form of adaptor structure wherein the body 81 is provided with transversely spaced longitudinally extending guide flanges 82 and 83 respectively that slidably engage opposite longitudinal side edges of the channel-shaped connecting bar 45 to guide the body 54 of the adaptor structure lengthwise of said bar. Other than this, the structure illustrated in Figs. 14 and 15 is similar to that shown in Figs. 10 to 13 inclusive.

What I claim as my invention is:

1. Actuating means for a plurality of independently mounted jalousie closures, and a single connecting bar connected to and supported by said closures; comprising

an actuating bar, and an adaptor structure pivotally connected to said actuating bar and including a body upon and slidably lengthwise of said connecting bar relative to a bore in said connecting bar, said body having an elongated slot in registration with said bore, and a nut slidably mounted upon said body and having a cylindrical axial extension slidably mounted in said elongated slot, said nut and extension having registering openings in registration with the bore aforesaid in said connecting bar, whereby an element mounted in said registering openings and bore is operable to connect said nut to said connecting bar.

2. Actuating means for a plurality of independently mounted jalousie closures, and a single connecting bar connected to and supported by said closures; comprising an actuating bar, and an adaptor structure pivotally connected to said actuating bar and including a body upon and slidably lengthwise of said connecting bar relative to a bore in said connecting bar, said body having an elongated slot in registration with said bore, a nut slidably mounted upon said body and having a cylindrical axial extension slidably mounted in said elongated slot, said nut and extension having registering openings in registration with the bore aforesaid in said connecting bar, and means mounted in said bore and said registering openings and connecting said adaptor structure to said connecting bar.

3. Actuating means for a plurality of independently mounted jalousie closures, and a single connecting bar connected to and supported by said closures; comprising an actuating bar, and an adaptor structure pivotally connected to said actuating bar and including a body upon and slidably lengthwise of said connecting bar relative to a bore in said connecting bar, said body having an elongated slot in registration with said bore, and a nut slidably mounted upon said body and having a cylindrical axial extension slidably mounted in said elongated slot, said nut and extension having registering openings in registration with the bore aforesaid in said connecting bar, whereby an element mounted in said registering openings and bore is operable to connect said nut to said connecting bar, a part of said body being shaped to guide said nut during sliding movement thereof and operable to prevent said nut from turning during such sliding movement.

4. Actuating means for a plurality of independently mounted jalousie closures, and a single connecting bar connected to and supported by said closures; comprising an actuating bar, and an adaptor structure pivotally connected to said actuating bar and including a body upon and slidably lengthwise of said connecting bar relative to a bore in said connecting bar, said body having an elongated slot in registration with said bore, a nut slidably mounted upon said body and having a cylindrical axial extension slidably mounted in said elongated slot, said nut and extension having registering openings in registration with the bore aforesaid in said connecting bar, a part of said body being shaped to guide said nut during sliding movement thereof and operable to prevent said nut from turning during such sliding movement, and means mounted in said bore and said registering openings and connecting said adaptor structure to said connecting bar.

5. Actuating means for a plurality of independently mounted jalousie closures, and a single connecting bar connected to and supported by said closures; comprising an actuating bar, and an adaptor structure pivotally connected to said actuating bar and including a body upon and slidably lengthwise of said connecting bar relative to a bore in said connecting bar, said body having an elongated slot in registration with said bore, a nut slidably mounted upon said body and having a cylindrical axial extension slidably mounted in said elongated slot, said nut and extension having registering openings in registration with the bore aforesaid in said connecting

bar, and a fastening element mounted in the bore aforesaid in said connecting bar and the registering openings in said nut and extension and connecting said adaptor structure to said connecting bar.

6. Actuating means for a plurality of independently mounted jalousie closures, and a single connecting bar connected to and supported by said closures; comprising an actuating bar, and an adaptor structure pivotally connected to said actuating bar and including a body upon and slidably lengthwise of said connecting bar relative to a bore in said connecting bar, said body having an elongated slot in registration with said bore, and a nut slidably mounted upon said body and having a cylindrical axial extension slidably mounted in said elongated slot, said nut and extension having registering openings in registration with the bore aforesaid in said connecting bar, whereby an element mounted in said registering openings and bore is operable to connect said nut to said connecting bar, said body being provided at one end of said elongated slot with a circular opening through which the cylindrical extension is inserted for engagement with said slot, a portion of said body at an edge of said circular opening being deformed and constituting a projection operable to prevent said cylindrical extension from registering with and being accidentally withdrawn from said circular opening after engaging said slot.

7. Actuating means for a plurality of independently mounted jalousie closures, and a single connecting bar connected to and supported by said closures; comprising an actuating bar, and an adaptor structure pivotally connected to said actuating bar and including a body upon and slideable lengthwise of said connecting bar relative to a bore in said connecting bar, said body having an elongated slot in registration with said bore, a nut slidably mounted upon said body and having a cylindrical axial extension within and movable lengthwise of said slot, said extension having an annular groove therein, said nut and extension having registering openings in registration with the bore aforesaid in said connecting bar, whereby an element mounted in said registering openings and bore is operable to connect said nut to said connecting bar, and said body being provided at opposite side edges of said slot with guide means engaging the annular groove in said extension during sliding movement of said nut and retaining the nut and cylindrical extension against displacement.

8. Actuating means for a plurality of independently mounted jalousie closures, and a single channel-shaped connecting bar connected to and supported by said closures; comprising an actuating bar, and an adaptor structure pivotally connected to said actuating bar and including a body upon and slidably lengthwise of said channel-shaped connecting bar relative to a bore in said connecting bar, said body having an elongated slot in registration with said bore, a nut slidably mounted upon said body and having a cylindrical axial extension within and movable lengthwise of said slot, said nut and extension having registering openings in registration with the bore aforesaid in said connecting bar, whereby an element mounted in said registering openings and bore is operable to connect said nut to said connecting bar, and said body being provided beyond opposite ends of said elongated slot with means engaging the channel of said connecting bar to guide said body lengthwise of said connecting bar.

9. Actuating means for a plurality of independently mounted jalousie closures, and a single channel-shaped connecting bar connected to and supported by said closures; comprising an actuating bar, and an adaptor structure pivotally connected to said actuating bar and including a body upon and slidably lengthwise of said channel-shaped connecting bar relative to a bore in said connecting bar, said body having an elongated slot in registration with said bore, a nut slidably mounted upon

said body and having a cylindrical axial extension within and movable lengthwise of said slot, said nut and extension having registering openings in registration with the bore aforesaid in said connecting bar, whereby an element mounted in said registering openings and bore is operable to connect said nut to said connecting bar, and said body being provided beyond opposite ends of said elongated slot with laterally projecting lugs engaging the channel of said connecting bar to guide said body lengthwise of said connecting bar.

10. Actuating means for a plurality of independently mounted jalousie closures, and a single connecting bar connected to and supported by said closures; comprising an actuating bar, and an adaptor structure pivotally connected to said actuating bar and including a body upon and slidably lengthwise of said connecting bar relative to a bore in said connecting bar, said body having an elongated slot in registration with said bore, a nut slidably mounted upon said body and having a cylindrical axial 15 extension within and movable lengthwise of said slot, said nut and extension having registering openings in registration with the bore aforesaid in said connecting bar, whereby an element mounted in said registering openings and bore is operable to connect said nut to said 20 connecting bar, and said body being provided with means engaging said connecting bar to guide said body lengthwise of said connecting bar.

11. Actuating means for a plurality of independently mounted jalousie closures, and a channel-shaped connecting bar connected to said closures and provided with a bore; comprising a manually operable actuating bar, and an adaptor structure having an elongated body pivotally connected to said actuating bar and extending and slidably lengthwise of the channel of said connecting bar, 30 said body having a longitudinally extending elongated slot extending lengthwise of said connecting bar and in registration with said bore, a nut slidably connected to said body to be retained thereby and movable lengthwise of said slot, said nut being in registration with said bore, 35 said body being provided beyond opposite ends of said elongated slot with laterally projecting lugs engaging the channel of said connecting bar for guiding said body lengthwise of said connecting bar, and means connecting said adaptor structure to said connecting bar, including 40 an element mounted in said bore and said nut.

45 all element mounted in said bore and said nut.

12. Actuating means for a plurality of independently mounted jalousie closures, and a connecting bar connected to said closures and provided with a bore; comprising a manually operable actuating bar, and an adaptor structure having an elongated body pivotally connected to said actuating bar and upon and slidably lengthwise of said connecting bar, said body having a longitudinally extending elongated slot extending lengthwise of said connecting bar and in registration with said bore, a nut 50 slidably connected to said body to be retained thereby and movable lengthwise of said slot, said nut being in registration with said bore, said elongated body being provided with transversely spaced longitudinally extending flanges engaging opposite side edges of said connecting bar for guiding said body lengthwise of said connecting bar, and means connecting said adaptor structure to said connecting bar, including an element mounted in 55 said bore and said nut.

60

13. Actuating means for a plurality of independently
65 mounted jalouse closures, and a connecting bar con-
nected to said closures and provided with a bore; com-
prising a manually operable actuating bar, and an adaptor
structure having a body pivotally connected to said
actuating bar and upon and slidably lengthwise of said
70 connecting bar, said body having an elongated slot ex-
tending lengthwise of said connecting bar and in regis-
tration with said bore, a nut slidably mounted upon said
body and having an axial extension within and slidable
lengthwise of said slot, said nut and said extension having
75 registering openings in registration with said bore, said

body being provided at one end of said slot with an opening through which said axial extension is inserted for engagement with said slot, a portion of said body at an edge of said opening being deformed and constituting a projection operable to prevent said extension from being accidentally withdrawn from said slot via said opening, said extension and said body having cooperating means guiding said extension lengthwise of said slot and preventing said extension from being accidentally withdrawn from said slot while sliding lengthwise thereof, and means connecting said adaptor structure to said connecting bar, including an element mounted in said bore and the registering openings in said extension and nut.

14. Actuating means for a plurality of independently mounted jalousie closures, and a connecting bar connected to said closures and provided with a bore; comprising a manually operable actuating bar extending lengthwise of said connecting bar, and means detachably connecting said actuating bar to said connecting bar including an adaptor structure having a body connected to said actuating bar and upon and slidably lengthwise of said connecting bar in substantially parallel relation thereto, said body having an elongated slot in registration with the bore aforesaid in said connecting bar, a nut slidably mounted on said body and having an opening in registration with said slot and said bore, said body having an elongated flange extending substantially parallel to the longitudinal median line of said elongated slot for guiding said nut lengthwise of said slot, and means connecting said adaptor structure to said connecting bar, including a fastener mounted in said bore, slot and opening.

15. Actuating means for a plurality of independently mounted jalousie closures, and a connecting bar connected to said closures and provided with a bore; comprising a manually operable actuating bar extending lengthwise of said connecting bar, and means detachably connecting said actuating bar to said connecting bar including an adaptor structure having a body connected to said actuating bar and upon and slidably lengthwise of said connecting bar in substantially parallel relation thereto, said body having an elongated slot in registration with the bore aforesaid in said connecting bar, a nut slidably connected to said body to be retained thereby and movable lengthwise of said slot, said nut having an opening in registration with said bore and said slot, said body having spaced projections engaging spaced portions of said connecting bar for guiding said body lengthwise of said connecting bar, and means connecting said adaptor structure to said connecting bar, including a fastener extending through said bore, slot and opening.

16. Actuating means for a plurality of independently mounted jalousie closures, and a connecting bar connected to said closures and provided with a bore; comprising a manually operable actuating bar extending lengthwise of said connecting bar, and means detachably connecting said actuating bar to said connecting bar including an adaptor structure having a body connected to said actuating bar and upon and slidably lengthwise of said connecting bar in substantially parallel relation thereto, said body having an elongated slot in registration with the bore aforesaid in said connecting bar, a nut slidably connected to said body to be retained thereby and movable lengthwise of said slot, said nut having an opening in registration with said bore and said slot, said body having upon one side thereof spaced projections engaging said connecting bar for guiding said body lengthwise of said connecting bar, and having upon the opposite side thereof an elongated flange engaging said nut for guiding the latter lengthwise of said slot, and means connecting said adaptor structure to said connecting bar, in-

cluding a fastener mounted in said bore, slot and opening.

17. Actuating means for a plurality of independently mounted jalousie closures, and a connecting bar connected to said closures and provided with a bore; comprising a manually operable actuating bar extending lengthwise of said connecting bar, and means detachably connecting said actuating bar to said connecting bar including an adaptor structure having an elongated body connected at one longitudinal side edge to said actuating bar and having one surface thereof substantially parallel and slidable relative to one surface of said connecting bar, said body having on the surface aforesaid thereof an elongated flange engaging a longitudinal side edge of said connecting bar for guiding the body of said adaptor structure lengthwise of said connecting bar, said body also having spaced relation to said elongated flange an opening in registration with the bore aforesaid in said connecting bar, and a fastener mounted in said bore and said opening.

18. Actuating means for a plurality of independently mounted jalousie closures, and a single connecting bar connected to and supported by said closures; comprising a manually operable actuating bar bodily free of and disposed in spaced substantially parallel relation to said connecting bar, an adaptor structure between said connecting bar and said actuating bar, said adaptor structure having a body connected to said actuating bar, said body having an elongated slot therethrough in registration with a bore in said connecting bar, a nut carried by said body and having an opening therethrough in registration with the slot in said body and with the bore in said connecting bar, and a connection between said adaptor structure and said connecting bar including a fastener engaging the bore in said connecting bar and the opening in said nut.

19. The actuating means described in claim 18, wherein the body is initially adjustable relative to the connecting bar to position the slot in registration with the bore, and the nut is initially adjustable relative to the body to position the opening in registration with the bore, to enable the fastener to be engaged with said bore and said opening as set forth.

20. The actuating means described in claim 19, wherein the fastener engageable with said bore and said opening when they are in registration is operable to hold the nut in fixed relation to said connecting bar while permitting relative movement between said body and said nut during movement of said actuating bar.

21. Actuating means for a plurality of independently mounted jalousie closures, and a single connecting bar connected to and supported by said closures; comprising a manually operable actuating bar bodily free of and disposed in spaced substantially parallel relation to said connecting bar, an adaptor structure between said connecting bar and said actuating bar, said adaptor structure being pivotally connected to said actuating bar and having an opening therethrough in registration with a bore in said connecting bar, and a connection between said adaptor structure and said connecting bar including a fastener extending through said bore and said opening, said adaptor structure being initially adjustable relative to said connecting bar to position the opening in registration with said bore to enable the fastener to be engaged with said bore and said opening as set forth.
